UNITED STATES PATENT OFFICE.

PAUL M. RAINY, OF WEST HOBOKEN, NEW JERSEY, ASSIGNOR, BY MESNE ASSIGNMENTS, TO WESTERN ELECTRIC COMPANY, INCORPORATED, OF NEW YORK, N. Y., A CORPORATION OF NEW YORK.

SYNCHRONIZING SYSTEM FOR MULTIPLEX TELEGRAPHS.

1,279,905.

Specification of Letters Patent. Patented Sept. 24, 1918.

Application filed March 26, 1914. Serial No. 827,315.

To all whom it may concern:

Be it known that I, PAUL M. RAINY, a citizen of the United States, residing at West Hoboken, in the county of Hudson and State of New Jersey, have invented a certain new and useful Improvement in Synchronizing Systems for Multiplex Telegraphs, of which the following is a full, clear, concise, and exact description.

10 This invention relates to improvements in the production and maintenance of synchronous motion between two or more rotating bodies which may be separated by any distance.

15 The invention relates particularly to a telegraph system wherein at one station a distributor is rotated at practically constant speed, and wherein at any other station a similar distributor is kept in step with the first, and variations either of acceleration or retardation are automatically corrected.

20 The principal objects of this invention are to provide improved means for altering the speed of one rotating body to keep it in synchronism with another and to provide an arrangement for furnishing a sharply defined correcting impulse, for controlling this change of speed, when required. To these ends the invention contemplates two independently movable bodies, one preferably being driven by a vibrating member, such as a tuning fork or its equivalent, the speed of such member being controlled by means of line current impulses through the agency of electromechanical means acting thereupon.

25 The local correcting impulses are provided and controlled through the agency of a pair of relays affected by line current impulses and coöperating to limit the correcting impulse to the time between the engagement of contacts of one relay and the disengagement of contacts of the other relay.

30 The above and other objects of this invention will be fully set forth in the following description and claims, and will be more readily understood by reference to the accompanying drawing wherein the preferred embodiment of the system is shown diagrammatically.

35 A distributor 1 at the transmitting end of the line is driven at a practically constant speed by any suitable mechanism, preferably a phonic wheel (not shown), which in turn may be understood to be driven by a tuning

fork or equivalent vibrating device, as is the case with respect to the receiving distributor 3 as hereinafter described. The impulses sent by this distributor may be either positive or negative, or any combination thereof, and on arriving at the receiving end of the line operate the line relay 2 which may be arranged for duplex working, as shown. At the receiving end of the line is a distributor 3 on which is mounted a plurality of sets of contacts which are shown developed and designated "Receiving," "Correcting" and "Sending." A phonic wheel 4 is kept in rotation by impulses from an electrically driven tuning fork 7, kept in vibration by the electromagnet 8.

40 Mounted on the shaft of the phonic wheel is a brush carrier 9 carrying a plurality of brushes which sweep over the sets of contacts on the distributor. The line relay 2 has its armature 10 connected to the battery 11 and thence to earth. The armature vibrates between two contacts 12 and 13, the armature ordinarily resting against the contact 13. A positive impulse arriving over the line moves the armature against the contact 12 where it will remain until a negative impulse arrives, when it moves over into engagement with the contact 13. A leak relay 14 is connected with the line relay 2 as shown with its terminal 15 connected to the contact 12 of the line relay through the resistance 16, and its terminal 17 connected to the contact 13 of the line relay through the resistance 18.

45 The common terminal of the relay is connected to the battery 11 and to ground. Its contact 19 is connected to the contact 12 above the resistance 16, while its contact 20 is connected to the contact 13 of the line relay above the resistance 18. The armature 21 of this leak relay is normally in engagement with the contact 19. A current passing through the relay from battery 11, contact 13, resistance 18, will hold the armature in engagement with the contact 19, where it will remain until the armature 10, of the line relay, is thrown over against contact 12, by the action of current over the line, when a current from battery 11, contact 12, resistance 16, will move the armature 21 from contact 19 into engagement with the contact 20.

50 It will be noted that in the development designated "correcting" alternate contacts

are connected together, each group of contacts being connected to a terminal of the controlling relay 22, while there is a common contact for all the separate contacts. This common contact is connected to the armature 21 of the leak relay 14. The armature of the controlling relay 22 is connected to the battery 23 and thence to ground. This armature operates between two contacts, one of which may be an idle contact, the other being connected to the winding of the magnet 24, for a purpose to be hereinafter described. The common point of this relay is connected through the resistance 25 to ground. One winding of the relay is connected by the conductor 26 to one-half the contacts of the "correcting" series of contacts, while the other winding is connected by the conductor 27 to the remaining half 20 of the contacts. The magnet 24 operates, through its armature, a buffer 28, which strikes against the tuning fork 7. It will be assumed that the distributor at the transmitting and receiving end of the line are 25 rotating in unison, with the brush carrier 9 moving the brushes over the distributor contacts at the same rate that the distributor brush at the transmitting end moves its brushes over its distributor to properly 30 translate the impulses at the receiving end of the line. The impulses will be assumed to be those designated line signals on the brush, the first impulse being positive and of unit length, the second negative of unit 35 length, the third positive of unit length and the fourth negative and of twice unit length, etc.

If we assume that for any reason the phonic wheel 4 is lagging behind the phonic wheel at the transmitting end of the line, and that if when this occurs a positive impulse arrives over the line wire the operation will be as follows: A positive impulse passing through the line relay 2 will cause the 40 armature 10 to move over into engagement with the contact 12 closing a circuit from battery 11, armature 10, contact 12, resistance 16, one winding of the relay 14, causing the armature 21 of the leak relay to move 45 over into engagement with the contact 20. Until the armature 21, however, pulls away from the contact 19, a pulse will be sent which may be traced as follows: battery 11, armature 10, contact 12, conductor 50 29, contact 19, armature 21, common contact of the correcting segments, brush, one contact of a group of the correcting segments, conductor 27, through one winding of the controlling relay 22, resistance 25, to 55 ground. This will cause the armature of the controlling relay to move over into engagement with its active contact, closing the circuit of the electromagnet 24 through the battery 23. Thus the local correcting impulse is definitely limited to the interval be-

tween the making of the line relay contacts and the breaking of the leak relay contacts. The energization of the electromagnet 24 causes it to attract its armature and the buffer 28 moves into engagement with the tuning fork 7, thereby increasing the speed of such tuning fork and thereby the speed of the phonic wheel 4. The phonic wheel 4 will immediately begin to run fast and will continue in such condition until the brush carrier 9 is in advance of the brush carrier at the transmitting end of the line when on change of current the armature 10 of the line relay moves out of engagement with the contact 13 and into engagement with the contact 12. 70

The armature 21 of the leak relay 14 will again cause a pulse of current to be sent from the battery 11, but as at this time the brush is in advance over the corresponding brush at the transmitting station, the pulse will pass by means of the brush through one of the other group of correcting segments and over the conductor 26, through the other winding of the controlling relay 22, causing 85 the armature of this relay to move over into engagement with its idle contact, thereby deenergizing the electromagnet 24 and moving the buffer 28 out of engagement with the tuning fork 7. 90

Positive or negative impulses are constantly arriving over the line, as the signals are sent from the distant station, but the effects described above only take place when the brushes at the receiving station lag or 100 lead a certain amount, and then only when the current in the line is changing from positive to negative or negative to positive. 95

In the following claims, the term vibrating member and similar expressions, means 105 a tuning fork or equivalent device, controlling the motor of the corresponding distributor.

What is claimed is:

1. In a synchronizing system, an arrangement for providing a correcting impulse comprising a transmission line extending between two stations and traversed by a sequence of current impulses, a relay under the influence of all such line current impulses, a second relay controlled by the first said relay, a source of current, circuit contacts controlled by each of said relays and co-operating with said source to provide a current impulse defined by the engagement 110 of certain of said contacts of the first relay and the disengagement of certain of said contacts of the second relay, a vibrating member, and electromechanical means actuated by said impulse for altering the rate 115 of vibration of said member. 120

2. In a synchronizing system, an arrangement for providing a correcting impulse comprising a transmission line extending between two stations and traversed by a 125 130

sequence of current impulses, a relay under the influence of all such line current impulses, an armature therefor, a second relay adapted to be actuated by each movement 5 of the armature of said first-mentioned relay, a source of current, circuit contacts controlled by each of said relays and coöperating with said source to provide a current impulse defined by the engagement of certain 10 of said contacts of the first relay and the disengagement of certain of said contacts of the second relay, a vibrating member, and electromechanical means actuated by said current impulse for altering the 15 rate of vibration of said member.

3. A synchronizing system comprising a rotatable body for providing current impulses, a transmission line associated therewith, a second independently rotatable body 20 also associated with said line, circuit contacts controlled by each of said relays and adapted to provide correcting current from the engagement of contacts of one of said relays to the disengagement of contacts of 25 the other of said relays, a vibrating member controlling the movement of said second body, and electromechanical means controlled by said correcting current for controlling the vibration of said member.

30 4. A synchronizing system comprising two independently vibrating members, means controlled by each for distributing signal current impulses of different polarities, and electromechanical means arranged to be controlled by current reversals for altering the period of vibration of one of said members.

5. A synchronizing system comprising a sending and a receiving rotary distributor, independently vibrating members for affecting the rotation of said distributor, 40 means for causing said sending distributor to impart reversals of current to said receiving distributor, and means arranged to mechanically vary the vibration of said member affecting the rotation of said receiving distributor upon the receipt of current reversals.

6. A synchronizing system comprising a transmission line, an independently movable current impulse distributing body associated with each end of said line, a vibrating member for controlling the movement of one of said bodies, and a buffer controlled by current impulses and adapted 55 to variably affect said member to alter the speed thereof.

7. A synchronizing system comprising a

transmission line, an independently movable current impulse distributing body associated with each end of said line, a vibrating member for controlling the movement of one of said bodies, and electromechanical means controlled by current impulses and adapted to variably affect said member to alter the speed thereof. 60

8. In a synchronizing system, an arrangement for providing a correcting impulse comprising a transmission line extending between two stations and adapted to be traversed by a sequence of impulses, a relay controlled by all such impulses, an armature for said relay, contacts controllable by said armature, an electromagnet controllable by said relay, an armature and contacts for said electromagnet, circuit connections between the contacts of said relay and the winding and contacts of said electromagnet, a source of current coöperating with said connections to provide a correcting impulse defined by the interval between the closing of a contact of said relay and the opening of a contact of said electromagnet, a vibrating member, and electromechanical means controlled by said correcting impulse for altering the rate of vibration of said 70 vibrating member. 75

9. In a synchronizing system, the combination of a transmission line extending between two stations and adapted to be traversed by a sequence of impulses, a rotary 90 current distributor, a vibrating member for affecting the operation of said distributor, a relay controlled by line current impulses, an armature for said relay, contacts controlled by said armature, an electromagnet, an armature and contacts for said electromagnet, circuit connections between the contacts of said relay and the winding and contacts of said electromagnet, a source of current coöperating with said connections to provide a 95 correcting impulse defined by the interval between the closing of a contact of said relay and the opening of a contact of said electromagnet, and electromechanical means affected by the correcting impulses so provided and coöperating with said vibrating member to control the operation of said distributor. 100

In witness whereof, I hereunto subscribe my name this 25 day of March A. D., 1914. 110

PAUL M. RAINY.
